UNITED STATES PATENT OFFICE.

HARRY HARDWICK, AMOS M. ULMER, AND FRANK FOWLER, OF PHILADELPHIA, PENNSYLVANIA.

YARN-REELING MACHINE.

SPECIFICATION forming part of Letters Patent No. 413,055, dated October 15, 1889.

Application filed March 11, 1887. Serial No. 230,493. (No model.)

To all whom it may concern:

Be it known that we, HARRY HARDWICK, AMOS M. ULMER, and FRANK FOWLER, all citizens of the United States, and residents of 5 Philadelphia, Pennsylvania, have invented certain Improvements in Yarn-Reeling Machines, of which the following is a specification.

The object of our invention is to provide 10 for the proper delivery of the yarn from the bobbins or cops in a reeling-frame without the necessity of changing the position of said bobbins or cops when they are partially unwound, and this object we attain in the manner hereinafter set forth, reference being had 15 to the accompanying drawings, in which—

Figure 1 is a rear view of a reel-frame constructed in accordance with our invention. Fig. 2 is a transverse section of the same on 20 the line 1 2, Fig. 1. Figs. 3 and 4 are diagrams illustrating the operation of the frame, and Fig. 5 is a perspective view of one of the spindles of the frame with its bearings and brake and parts of the fixed bars of the frame.

25 A represents the fixed frame of the machine, to suitable bearings in which is adapted the shaft B of the reel, the latter being constructed in any of the usual ways.

To longitudinal bars *a* at the rear of the 30 frame are secured bearings *b* for the lower portions of spindles *D*, which carry the cops *x*, from which the yarn is to be unwound upon the reel, the yarn passing from the cops through a guide-eye *w* on a bar *d*, and thence 35 through a guide-eye *y* on the traverse-bar *f*. Usually the bar *d* is fixed and the frame is provided with two sets of bearings for the spindles *D*, one set serving to hold said spindles rigidly in an upright position and 40 the other set serving to receive the spindles in a horizontal position and to permit them to turn. The spindles are adapted to the fixed bearings, and are held in an upright position, as shown in Fig. 1, for instance, 45 while the main body of yarn is being unwound therefrom, the yarn being drawn off in a direction substantially parallel with the spindle. When the supply of yarn from the spindle has been reduced, however, this 50 method of unwinding is impracticable, as the

yarn has a tendency to wrap around the projecting portion of the spindle and interfere with its free delivery, or the strand will sometimes catch under the cop and be broken or pull the cop from the spindle, so as to cause 55 waste. Ordinarily, therefore, the spindle is removed from its fixed bearings and applied to the horizontal bearings when the unwinding of the yarn has been partially completed, the spindle being permitted to rotate while the re- 60 mainder of yarn is being unwound therefrom. In order to avoid the necessity of this shifting of the spindles, we mount them in the bearings *b*, so that they are free to rotate therein, and we provide means for changing the course 65 of the yarn in its delivery from the spindle, so that during the first part of the unwinding operation it will be drawn from the spindle in a direction substantially parallel with the same, as usual, but during the latter part of 70 the unwinding operation will be drawn off in a direction substantially at right angles to the axis of the spindle, the latter rotating in its bearings to permit such delivery of the 75 yarn. In the machine shown in Figs. 1 and 2 this is effected by the vertical adjustment of the bar *d*, carrying the upper guide-eyes *w*, said bar being guided in slotted standards *F* on the frame, and being provided with suitable counter-weights *g*, which are connected 80 to the bar by chains *h*, passing over conveniently-arranged pulleys *i*. When the bar is in the elevated position, the guide-eye *w* occupies such a position in respect to the spindle that the yarn will be drawn from the end 85 of the same, as usual, and as shown in Fig. 3; but by depressing the bar the eye *w* is caused to occupy such a relation to the spindle that the yarn can be drawn therefrom, as shown in Fig. 4, the spindle rotating during this 90 operation. It will thus be seen that by simply depressing the bar *d* the shifting of the spindles from one set of bearings to another is rendered unnecessary. Suitable weighted catches *p* serve to retain the bar *d* in either 95 the elevated or depressed position.

In order to prevent overrunning of the spindle during the time that the yarn is being drawn therefrom, as shown in Fig. 4, we hang to brackets *m* on one of the bars *a* 100

curved arms *n*, one for each spindle, these arms having at the lower ends blocks *n'*, which bear upon the spindles and serve as brakes for the same, the blocks being, if desired, faced with leather or other frictional material.

The shaft of the reel is driven by means of a belt from any available counter-shaft, one end of said reel-shaft being provided with a fast pulley *J* and loose pulley *J'* for receiving the belt, and said shaft also having a bevel-wheel *s*, which gears into a bevel-pinion *s'* on a shaft *t*, having at the upper end a disk *v*, with crank-pin *v'*, adapted to a slot in a bar *u*, connected to the traverse-bar *f*, so that a proper reciprocating motion will be imparted to the latter. The means for driving the reel and traverse-bar, however, are common in machines as at present constructed, and form no part of our invention, but may be modified as circumstances may suggest.

We are aware that it has been proposed to provide a yarn-spooling machine with vertical cop-shafts which could be rotated and also with fixed guides, one set of which could be used when the cop was being rotated and the other set when the yarn was being drawn endwise from the cop; hence we do not claim such construction.

30 We claim as our invention—

1. The combination of the reel and its shaft, the spindles, bearings in which said spindles are free to turn, and a bar carrying guides for the yarn, said bar being movable vertically, so as to change the direction of deliv-

ery of the yarn from the spindles, all substantially as specified.

2. The combination of the reel and its shaft, the spindles, and bearings in which said spindles are free to turn, a movable bar having 40 guides for the yarn, and weights connected to said bar and serving to counterbalance the same, all substantially as specified.

3. The combination of the reel and its shaft, the spindles, and bearings in which said spindles are free to turn, a bar having guides for 45 the yarn and movable vertically, so as to change the direction of delivery of the yarn from the spindles, and a traverse-bar having guides for receiving the yarn after the same 50 passes through the guides of the shifting-bar, all substantially as specified.

4. The combination of the reel and its shaft, the spindles, bearings in which said spindles are free to turn, a bar having guides for the 55 yarn, and movable so as to change the direction of delivery of the yarn from the spindles, and hooked catches for retaining said bar in either of its extreme positions, all substantially as specified.

In testimony whereof we have signed our names to this specification in the presence of two subscribing witnesses.

HARRY HARDWICK,
AMOS M. ULMER,
FRANK FOWLER.
